ATTORNEY

UNITED STATES PATENT OFFICE.

LEWIS F. CAVAGNA, OF WATERBURY, CONNECTICUT.

METAL RAILROAD TIE.

Application filed March 1, 1927. Serial No. 171,788.

This invention relates to railroad ties, and more particularly to a hollow cross-tie constructed of metal.

One object of this invention is to provide a railroad cross-tie having means for adjustably clamping a pair of rails.

A further object is to provide a hollow cross-tie of the above nature having a pair of side channels for receiving the rails and a central channel for housing adjusting means for the rail clamps.

A further object of this invention is to provide safety guards or wear strips adapted to be received in the side channels for supporting the rail and protecting said side channels from wear.

A further object is to provide a device of the above nature which will be simple in construction, inexpensive to manufacture, easy to install and manipulate, compact, and very efficient and durable in use.

With these and other objects in view there has been illustrated on the accompanying drawing one form in which the invention may be conveniently embodied in practice.

Fig. 1 represents a perspective view, with certain parts broken away, of a cross-tie embodying the principles of the invention.

Fig. 2 is a longitudinal sectional view of the same.

Fig. 3 is a transverse sectional view, taken along the line 3—3 of Fig. 2, looking in the direction of the arrows.

Fig. 4 is a fragmentary sectional view of a portion of the cross-tie showing the construction of the adjusting wheel and locking dog.

Referring now to the drawings in which like reference numerals denote corresponding parts throughout the several views, the cross-tie comprises a generally rectangular hollow casing having sides 10 and 11, ends 12 and 13, and a detachable bottom 14, the latter being held in place by screw bolts 15, said bolts 15 being adapted to be screwed into the enlarged sockets 16 in the ends 12 and 13, respectively, of said casing.

The cross-tie is provided in its top face adjacent its ends with a pair of end channels 17 and 18, each of which is adapted to receive a channel-shaped safety guard or wear strip 19 having flanges 20 adapted to rest upon the top of said casing adjacent the channels 17 and 18. The safety guards 19 are

adapted to support a pair of rails 21 and 22 and to protect the side channels 17 and 18 from wear.

Located between the side channels 17 and 18, and being of somewhat greater depth, is a central channel 23 adapted to be protected from the weather by an apron cover member 24. The member 24 has a pair of downwardly extending side flanges 25, said flanges 25 being connected by a pair of transverse ribs 26 located on the lower face of said cover member 24, said ribs 26 being adapted to seat against the upper corners 27 of said central channel. The side flanges 25 terminate at a point below the bottom of the central channel 23, thus preventing the entrance of dirt or other materials.

In order to hold the rails 21 and 22 securely in the channels 17 and 18, provision is made of two pairs of rail clamps 28 and 29, said clamps having horizontal tapered jaw members 30 and 31 adapted to extend toward each other through rectangular openings 32 and 33 in the side faces of the side channels 17 and 18 and the safety guards 19 respectively.

Each of the tapered jaw members 30 and 31 is provided with a depending bracket 34 and 35, said brackets having threaded holes of different diameters and of opposite pitches for receiving a pair of draw-rods 36. Each draw-rod 36 has a pair of threaded sections 37 and 38 of different diameters and opposite pitches adapted to be received in the threaded holes of the brackets 34 and 35 respectively. The brackets 34 and 35, and the jaw members 30 and 31 are strengthened by inclined brace members 39.

The draw-rods 36 are adapted to lie in horizontal alignment with each other, and as clearly shown in Fig. 2, said draw-rods have reduced inner extremities 40 located within the central channel 23 previously described.

In order to limit the inward movements of the draw-rods 36, each of them is provided with a collar 41 adapted to rest against the inside face of the hollow cross-tie casing. Adjacent the collar 41 and located on the outside face of the tie within the central channel 23, provision is made of an adjusting wheel 42 having two sets of spaced apertures 43 and 44, equally spaced around its periphery. The apertures 43 of the adjusting wheel 42 are provided for the purpose of

receiving an adjusting rod 45, shown in dotted lines in Fig. 4, whereby the railroad trackman or other employee will be enabled to readily force the clamping jaws 30 and 31 upon the rail by rotating the wheel 42. After the draw-rods and jaws have been adjusted into clamping position with the desired tension, as shown at the right of Fig. 2, the jaws 30 and 31 will be held against spreading apart by a locking dog 46 pivoted on a pin 47, said dog 46 being frictionally held against the side wall of the central recess 23. The dog 46 has a depending tooth 47^a for engaging the apertures 44 of the wheel 42. The adjusting wheel 42 is non-rotatably held upon the inner end of the draw-bar 36, as by a key 48, as most clearly shown in Fig. 4.

In order to provide an additional support for the rail on curves, a rail brace strip 49 is provided, said strip having an inclined section 50 for engaging the top of the rail and being secured to the guard plate 19, as by rivets 51, as clearly shown in Fig. 2.

In operation, the safety guards 19 will first be laid within the side channels 17 and 18. The rails 21 and 22 will then be placed within said guards, as shown at the left of Fig. 2. The apron cover 24 will then be removed, whereupon the operator will rotate the adjusting wheels 42, by means of the tool 45, in such directions as to cause the draw-rods 36 to pull each pair of jaw members 30 and 31 from the position shown at the left of Fig. 2 to the position shown at the right of said figure. The locking dogs 46 will then be manually forced down into one of the apertures 44 for preventing the adjusting wheel 42 from loosening. It will be understood that when the rails are to be removed from the tie, the operation will be the reverse of that just described, and that the locking dogs 46 will be held in raised position by reason of their frictional contact with the side walls of the central channel.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a railroad cross-tie, a hollow casing having a transverse channel, and a U-shaped wear strip seated in said channel for receiving a rail, said wear strip having outwardly-extending flanges to fit over the top of the cross-tie.

2. In a railroad cross-tie, a hollow casing having a pair of transverse channels, and a pair of U-shaped wear strips seated in said channels for supporting a pair of rails, each of said wear strips having outwardly-extending flanges to fit over the top of the cross-tie. 70

3. In a railroad cross-tie, a hollow casing having a transverse channel for supporting a rail, a second transverse channel, and means adjustable from said second transverse channel for clamping said rail within said channel. 75

4. In a railroad cross-tie, a casing having a transverse channel for supporting a rail, a second transverse channel, and means adjustable from said second transverse channel for clamping said rail within said channel. 80

5. In a railroad cross-tie, a hollow casing having a pair of transverse channels for supporting a pair of rails respectively, a third transverse channel between said rails, and means operable from said third transverse channel for clamping said rails within said rail channels. 85

6. In a railroad cross-tie, a hollow casing having a pair of transverse channels located near the ends of said tie for supporting a pair of rails respectively, a third transverse channel between said rails, and means operable from said third transverse channel for clamping said rails within said rail channels. 90

7. In a railroad cross-tie, a hollow casing having a pair of transverse end channels for supporting a pair of rails respectively, a central transverse channel located between said side channels, and means operable from within said central channel for clamping said rails within said side channels. 100

8. In a railroad cross-tie, a hollow casing having a pair of transverse end channels for supporting a pair of rails respectively, a central transverse channel located between said side channels, and means operable from within said central channel for adjustably clamping said rails within said side channels. 105

9. In a railroad cross-tie, a hollow casing having a transverse channel for receiving a rail, a pair of slideable rail clamps for engaging opposite sides of said rail, and means located within said casing for engaging said rail clamps and forcing them against said rail. 115

10. In a railroad cross-tie, a hollow casing having a transverse channel for receiving a rail, a pair of slideable rail clamps for engaging opposite sides of said rail, a rod having threaded engagement with both of said rail clamps, the portions of said rod where it engages said clamps being of different diameters and of opposite pitch. 120

11. In a railroad cross-tie, a hollow casing having a transverse channel for receiving a rail, a pair of slideable rail clamps for engaging opposite sides of said rail, a rod having threaded engagement with both of said rail 125

clamps, the portions of said rod where it engages said clamps being of different diameters and of opposite pitch, and a rotary adjusting wheel on the end of said rod.

5. 12. In a railroad cross-tie, a hollow casing having a transverse channel for receiving a rail, a pair of slideable rail clamps for engaging opposite sides of said rail, a rod having threaded engagement with both of said rail clamps, the portions of said rod where it engages said clamps being of different diameters and of opposite pitch, a rotary adjusting wheel on the end of said rod, and means for locking said adjusting wheel in 10 any desired position.

13. In a railroad cross-tie, a hollow casing having a pair of transverse side channels for

receiving and supporting a pair of rails respectively, a transverse central channel located between said side channels, each of said side channels having a pair of slideable rail clamps projecting therethrough, rods within said casing, and means on said rods for moving said rail clamps in opposite directions to clamp said rails.

20 25 14. In a railroad cross-tie, a hollow casing having a transverse channel, a wear strip seated in said channel for receiving a rail, and a brace strip secured to the outer edge of said wear strip for providing an additional support for said rail on curves.

30 In testimony whereof, I have affixed my signature to this specification.

LEWIS F. CAVAGNA.
